E. HIRSCH

SANDING DEVICE

Filed Oct. 4, 1922

INVENTOR
EDWARD HIRSCH

BY
Morris Firestone ATTORNEY

Patented Jan. 1, 1924.

UNITED STATES PATENT OFFICE.

EDWARD HIRSCH, OF NEW YORK, N. Y.

SANDING DEVICE.

Application filed October 4, 1922. Serial No. 592,247.

To all whom it may concern:

Be it known that I, EDWARD HIRSCH, a citizen of the United States, residing at New York city, in the county of New York and State of New York, have invented certain new and useful Improvements in Sanding Devices, of which the following is a specification.

This invention relates to sanding devices for vehicles.

One object of the invention is to provide a practical and efficient sanding device of the character described which shall positively function to reduce to a minimum the skidding of motor vehicles.

Another object of the invention is to provide a sanding device of the character described which shall be simple and easy in operation and readily attachable to an automobile.

A further object is to provide a sanding device of the character described with means for keeping the sand dry and warm and preventing same from congealing or solidifying.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawings, in which is shown one of various possible illustrative embodiment of this invention,

Fig. 1 is a partial side elevational view of a touring car partly in cross-section provided with a sanding device embodying this invention;

Fig. 2 is a diagrammatic partial plan view thereof;

Fig. 3 is an enlarged detailed cross-sectional view of the sand box taken along line 3-3 of Fig. 1; and

Fig. 4 is a partial perspective view showing an embodiment of the invention in place on the frame of an automobile truck.

Referring in detail to the drawing, in Figs. 1, 2 and 3, my invention is illustrated as applied to a touring car of any well-known construction. In these figures 10 indicates the car body and 11 the floor thereof. The sanding device comprises a sand

box or hopper 13 suitably secured underneath the car body and made of any suitable material, preferably sheet metal. I make the sand box preferably of double walled construction so as to enclose an air space 14 between the inner wall 15 and the outer wall 16 of the box, for the purpose hereinafter described. Extending from the hopper is a spout or outlet tube 17 bent toward the rear wheel 18 of the car so that the sand when released from the hopper will be deposited directly in front of said wheel. The delivery of the sand from the hopper is controlled by means of a valve or door 19 operated by a suitable lever arrangement adapted to be actuated by the driver. In the form shown in the drawing, a hand lever 20 is arranged in front of the driver's seat adjacent the steering wheel 21. Connected to the lower end of said hand lever as at 22 is a longitudinal rod 23, the other end 24 of which is connected as at 25 to a lever 26^a pivoted on the cross shaft 27. A similar lever 26^b is pivoted to the same shaft 27 and has connected thereto another longitudinal rod 28, the forward end of which is pivotally connected as at 29 to the link 30 to which the valve 19 is operatively secured as at 31. Mounted on the rod 23 adjacent the rear end thereof is a coil spring 32 held between a collar 33 and a bracket 34 arranged in spaced relation on said rod. If desired, the hand lever 20 may be provided with a projection 20^a adapted to enter in a corresponding notch 35^a of a segment 36 and to be held in place by means of a locking rod 20^b when the hand lever is thrown forward.

If desired, one sand box such as described may be provided for each of the rear wheels of the car as shown in Fig. 2 and operated from the same hand lever and link mechanism, the cross shaft 27 extending clear across the automobile chassis for connection as at 37 with the link 38 connected to the valve or door of the other sand box 39. In this way, the operation of the hand lever 20 will simultaneously open or close the valves in each of the sand boxes 13 and 39.

Difficulty has been experienced with sanding devices of this character in that the sand very often freezes in cold weather or becomes lumpy due to dampness. My invention includes means for constantly heating the sand in the sand box so as to prevent congelation or solidification of the

2
sand. To accomplish this end in a cheap and efficient manner, I preferably employ the heat of the exhaust gases. In the form shown in the drawing, I provide on the 5 exhaust outlet 40 an air chamber 41 which surrounds the exhaust outlet and communicates with the air space 14 by means of a connecting tube 42. The air chamber 41 is provided with perforations 41' through 10 which air enters from the outside. Perforations 13' are likewise provided adjacent to top of the hopper 13, communicating with the air space 14, thus making this air space open to the outside. The air in the chamber 15 is subjected to the heat of the exhaust gases issuing from the exhaust manifold 43 through the exhaust outlet 40. In this way the air in the air space 14 surrounding the sand 44 in the sand box is kept warm and 20 the sand consequently kept sufficiently dry so as to be always available and flow freely from the spout 17. To further insure the maintaining of the sand at a proper temperature, I provide on the outside of the 25 hopper a covering of asbestos or the like heat insulating material 45.

In Fig. 4 I have shown an embodiment 30 of the invention as applied to an automobile truck. In this form the sand box is mounted on a platform 45^a which is suspended from the side frame 46 of the truck by means of straps 47 suitably fastened or riveted to the frame. Inasmuch as in this construction the sand box is exposed, I preferably enclose the same in a rectangular box 48 having a lid 49 which may be locked by a pad-lock 50.

In the form shown in Figs. 1, 2 and 3, the 40 hopper is located preferably underneath the floor of the touring car adjacent the rear seat, the floor being cut out as at 51 to provide a shoulder 52 on which rests corresponding flanged portions 53, 54 of the interior and exterior walls of the hopper. A 45 cover 55 is provided so as to be flush with the floor and to be lifted or slid off when access is desired to the hopper. Preferably I provide a sieve member 56 at the top of the hopper so that any foreign material 50 such as pebbles and the like may be sifted out from the sand as it is placed in the hopper. The cover 56 is preferably spaced from the hopper by means of a thin washer or layer of material 57.

55 The operation of the device will be clear. When the vehicle is moving on wet ground, or at the time of emergency the driver throws the hand lever 20 forward thus opening the valve 19 through the link and lever 60 mechanism described. In this operation the rod 23 moves rearward and collar 33 thereon compresses the spring 32 against the bracket 34. If the operator desires the sand to be supplied in front of the rear 65 wheels continuously for a period of time, the

hand lever 20 is kept in forward position by the engagement of the projection 20^a in the notch 35^a. When the hand lever is released, the tension of the spring acts to push the rod 23 forward, thus reversing the operation and closing the valve 19 as will be readily understood.

70 It will thus be seen that there is provided a device in which the several objects of this invention are achieved and which is well adapted to meet the conditions of practical use.

75 As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I 80 claim as new and desire to secure by Letters Patent:—

1. A sanding device for motor vehicles comprising a sand container adapted to be secured to the vehicle, a delivery spout extending from said container and disposed in front of the rear wheel of the vehicle, said container having an enclosed air space in communication with an air compartment heated by the exhaust manifold of the vehicle for heating the air in said space for the purpose described and specified.

90 2. A sanding device for motor vehicles comprising a sand container adapted to be secured to the vehicle, a delivery spout extending from said container and disposed in front of the rear wheel of the vehicle, said container being of double walled construction so as to provide an air space, a connecting tube in communication at one end with 95 said air space and at the other end with an air chamber surrounding the exhaust pipe of the exhaust manifold of the vehicle whereby the air in said air space is heated by the exhaust gases passing through said exhaust pipe.

100 3. In a sanding device for motor vehicles the combination of a sand container adapted to be secured to the vehicle, a delivery spout extending from said container and disposed in front of a rear wheel of the vehicle, said delivery spout being provided with a valve, 105 mechanism for operating said valve to open and close said delivery spout, means for operating said mechanism including a hand lever disposed adjacent the driver's seat, said valve operating mechanism including automatic resetting means for restoring the valve to its normally closed position when said hand lever is released.

110 4. In a sanding device for motor vehicles the combination of a sand container adapted to be secured to the vehicle, a delivery spout extending from said container and disposed 115 in front of a rear wheel of the vehicle, said

delivery spout being provided with a valve, mechanism for operating said valve to open and close said delivery spout, means for operating said mechanism including a hand lever disposed adjacent the driver's seat, said valve operating mechanism including automatic resetting means for restoring the

valve to its normally closed position when said hand lever is released, and means for maintaining said hand lever in position to keep the valve open.

In testimony whereof I affix my signature.

EDWARD HIRSCH.
